UNITED STATES PATENT OFFICE

FREDERICK F. ZEIER, OF CHICAGO, ILLINOIS, ASSIGNOR TO UNION SPECIAL MACHINE COMPANY, OF CHICAGO, ILLINOIS, A CORPORATION OF ILLINOIS

LOOPER MECHANISM FOR SEWING MACHINES

Application filed May 13, 1929. Serial No. 362,680.

The invention relates to new and useful improvements in a looper mechanism for sewing machines, and more particularly to a mechanism for giving to said looper a movement into and out of the needle loop and also a needle avoiding movement.

An object of the invention is to provide a looper actuating mechanism wherein all the movements for the looper are derived from the movements of an eccentric strap.

A further object of the invention is to provide a looper operating mechanism of the above type wherein the endwise movements of the eccentric strap are utilized for moving the looper into and out of the needle thread loop while the lateral movements of the eccentric strap are utilized for imparting a needle avoiding movement to the looper.

These and other objects will in part be obvious and will in part be hereinafter more fully disclosed.

In the drawings which show by way of illustration one embodiment of the invention:-

Fig. 1 is a plan view of the looper operating mechanism.

Fig. 2 is a section through the bed of the machine showing the looper operating mechanism in side view.

Fig. 3 is a sectional view on the line 3—3 of Fig. 2.

Fig. 4 is a view similar to Fig. 3, but showing the eccentric strap in a different position.

The invention is directed to a looper operating mechanism for sewing machines. The looper is of the thread carrying type and is mounted on a carrier which is oscillated for moving the looper into and out of the needle thread loop. The looper carrier is in turn mounted on a looper support which is oscillated for imparting the needle avoiding movement to the looper. On the main shaft of the machine is an eccentric. Cooperating with the eccentric is an eccentric strap which is connected at its free end to an arm carried by a rock shaft so that the longitudinal movements of the eccentric strap as the main shaft rotates oscillate said rock shaft. The rock shaft carries an arm which is connected through a link to the looper carrier and thus

the oscillations of the rock shaft move the looper into and out of the needle thread loop. The eccentric strap is provided with a projecting portion adjacent the eccentric. Attached to this projecting portion is a stud 55 and a link connected to said stud is in turn connected to a slotted arm which is fixed to the looper support. During the rotations of the eccentric the upper end of the eccentric strap will be given a lateral movement and through this link connection the looper support is oscillated and a needle avoiding movement given to the looper.

Referring more in detail to the drawings, the invention is shown as applied to a sewing machine having a supporting bed 1 in which is mounted the main operating shaft 2. The loopers are indicated at 3 and are of the thread carrying type. These loopers are mounted in a looper carrier 4 which is pivoted at 5 to a looper support 6. The looper support 6 is attached at one end to a pivot stud 7 and at its other end to a short shaft 8. This short shaft 8 and the pivot stud are a part of the looper support. The main shaft 2 carries an eccentric 9 (see Figs. 3 and 4).

Cooperating with this eccentric 9 is an eccentric strap 10. The eccentric strap is connected to a ball stud 11 on an arm 12 attached to a sleeve 13 fixed to a shaft 14. Mounted on this sleeve 13 is an arm 15. A link 16 is pivoted at 17 to the arm 15 and is pivoted at 18 to the looper carrier 4. As the main shaft rotates the eccentric strap will be given a movement which will cause the ball stud 11 to move up and down in a vertical plane and impart oscillations to the shaft 14 and the arm 15 carried thereby. The oscillating arm 15 through the link 16 will oscillate the looper carrier and move the looper into and out of the needle thread loops. The eccentric strap 10 is provided with a lateral extension 19. Mounted on the end of the shaft 8 forming a part of the looper support is a sleeve 20 carrying a depending arm 21 which is formed with a slot 22. Mounted in this slot 22 is a ball stud 23 which is capable of being shifted in the slot and secured in adjusted positions by a nut 24. A link 25 engages the ball stud 100

23. This link at its other end carries a ball stud 26.

The extension 19 of the eccentric strap engages the ball stud 26. The eccentric rotates in the direction of the arrow in Figs. 3 and 4. When it moves from its extreme upper throw, as shown in Fig. 3, to its extreme lower throw, as shown in Fig. 4, it will cause the upper end of the eccentric strap to move laterally turning about the center of the ball stud 11 as an axis. This lateral shift of the upper end of the eccentric strap through the link 25 will impart oscillations to the arm 21 and the shaft 8 to which it is connected. This shaft 8, as noted above, is a part of the looper support and will, therefore, give a lateral oscillation or needle avoiding movement to the looper. The extent of needle avoiding movement given to the looper may be varied by shifting the stud 23 in the slot 22.

The extension 19 to which the ball stud 26 is connected is below the center of the main shaft even when the eccentric is at its extreme upper throw as viewed in Fig. 3. It is still further below the center of the shaft when the eccentric is at its extreme lower throw as viewed in Fig. 4. The lateral movements of the eccentric are, therefore, somewhat modified in the lateral movements imparted to the ball stud 26. When the eccentric strap is in the position shown in Fig. 3 the looper is all the way back. As the eccentric turns in a counter-clockwise direction, the stud 11 will be moved downward and this will cause the looper to move forward into the needle thread loop. When the looper is at the rear end of its stroke, the eccentric strap is midway between the extremes of its lateral throw and as the looper starts forward the stud 26 will be moved to the left as viewed in Fig. 3, which will oscillate the shaft 8 in a clockwise direction and move the looper so that it will pass the needle on the rear side thereof as viewed from the front of the machine. As the eccentric continues its rotation the looper is retracted and the eccentric strap will be shifted to the right as viewed in Figs. 3 and 4 and this will move the looper so that on its retracting path it is positioned on the opposite side of the needle path, that is, in front of the needle as viewed by the operator. This needle avoiding movement of the looper positions the looper thread triangle for the needle to enter the same.

It will be apparent from the above that a looper operating mechanism has been provided wherein the endwise movements of the eccentric strap are utilized for moving the looper into and out of the needle thread loop and the lateral movements of the eccentric strap at the end thereof engaging the eccentric are utilized for imparting the needle avoiding movement to the looper. This makes a very simple structure in which the

movements of the four motion looper are all positively obtained from a single eccentric strap.

It is obvious that minor changes in the details of construction may be made without departing from the spirit of the invention as set forth in the appended claim. 70

Having fully described my invention what I claim as new and desire to secure by Letters Patent, is:—

A looper mechanism for sewing machines including a looper, a carrier therefor, a looper support to which the carrier is pivoted, said looper support including a supporting shaft, a main shaft at one side of, below and parallel with the supporting shaft, an eccentric thereon, a rock shaft at right angles to the main shaft, an arm carried thereby, a link connecting said arm to said looper carrier, a second arm carried by said rock shaft, an eccentric strap cooperating with the eccentric and connected to said last-named arm, an arm on the supporting shaft depending therefrom, a link pivoted to the eccentric strap adjacent the eccentric and having an adjustable connection with the arm on the supporting shaft whereby the lateral movements of the eccentric strap impart an oscillation to said supporting shaft. 80

In testimony whereof, I affix my signature. 85
